Letters Patent No. 4505. Dated Nov. 13. 1866.

Design for a Tobacco Pipe.

The Schedule referred to in these Letters Patent and making part of the same.

To all whom it may concern:

Be it known that Joseph Harvey of Philadelphia County of Philadelphia, State of Pennsylvania have invented or produced a new and original Design for a Tobacco Pipe, and do hereby declare the accompanying Drawing with the following explanation of the same to form a full, clear and exact description of the said Design.

The figure in this accompanying drawing represents the tobacco pipe A, being the bowl and B, the stem, to the form of either of which this application for a patent does not relate.

C is a cup or receiver of the form shown in the drawing and to which is secured the bowl A, and from the cup projects a tube D, terminating in a socket for the reception of the lower end of the stem B.

I claim, the Design for the part of a tobacco pipe, substantially as shown in and by the accompanying drawing.

In testimony whereof, I have signed my name to this Specification in the presence of two subscribing witnesses

Witnessed,

W. A. D. Pierce.
